UNITED STATES PATENT OFFICE.

JAMES ALSTON HARMON, OF HAWKINSVILLE, GEORGIA.

LAWN-SPRINKLER.

SPECIFICATION forming part of Letters Patent No. 650,835, dated June 5, 1900.

Application filed August 12, 1899. Serial No. 726,974. (No model.)

To all whom it may concern:

Be it known that I, JAMES ALSTON HARMON, a citizen of the United States, residing at Hawkinsville, in the county of Pulaski and 5 State of Georgia, have invented a new and useful Lawn-Sprinkler, of which the following is a specification, reference being had to the accompanying drawings, forming a part thereof.

10 Figure 1 is a vertical section of the entire machine. Fig. 2 is a view of the paddle-wheel when removed from the other parts of the machine.

In Fig. 1 the tapering staff comes to a sharp 15 point at the lower end to hold the sprinkler firmly in the ground when in use. The upper end at G has small hole with threads for holding the paddle-wheel in place. From the top the staff tapers downward to shoulder.

20 Below the shoulder, running down for an inch or more, are threads cut on staff. The purpose of the threads is to hold in position the T-shaped tubing or casing. (See G F, Fig. 1.) The further object of these threads 25 is to form an adjustment for the regulating of the volume of water by running the casing up or down, and thus enlarging the opening at the top of casing or T-tube.

As seen in Fig. 1, the lower end of the tube 30 or casing screws onto the staff at the shoulder, thus making adjustment spoken of above. The top of casing is open to allow the passage of the water upward. The end at right angles F is screwed into the hose through 35 which comes the supply of water.

Fig. 2 represents the paddle-wheel, the arms of which are twisted to an angle of about forty-five degrees, as in case of windmill, in the center of which is an eye or bearing, and 40 it is mounted on top of staff at G by suitable bearings. Thus the water coming through hose and through tube-casing at F rushes out at the top, striking the paddle-wheel, setting it in rapid motion, and the quick revolutions 45 of the paddle-wheel distribute the water for

a space of many feet in diameter. It is apparent that any number of these may be grouped together, thus forming combinations.

These lawn-sprinklers are to be made of suitable metals.

Having described my invention, what I claim as new, and desire to secure by Letters Patent, is—

1. A lawn-sprinkler, comprising an upright staff, tapering to a point at its lower end and 55 diminishing from its upper end to shoulder H J, and provided with threads from said shoulder downward, to receive and hold in position a casing T, and for the purpose of regulating the flow of water, substantially as 60 described.

2. A lawn-sprinkler, comprising an upright staff, on which is mounted T-casing by means of a thread in lower end of said casing answering to threads on the staff by which the 65 casing is firmly held in position and by which the flow of the water is regulated and the character of the spray determined, the end of the casing at right angles to main stem being threaded for the adjustment of hose and 70 the upper end of said casing receiving the upper end of staff with sufficient space between them to allow the passage of water outward the quantity being determined by screwing casing up or down on staff substantially 75 as described.

3. A lawn-sprinkler, comprising an upright staff on which is mounted a T-casing with suitable adjustments above which and on the top of said staff is mounted a paddle-wheel 80 by means of a screw passing through center of paddle-wheel and into center of upper end of staff, said paddle-wheel having arms thin and flat and twisted to suitable angle, substantially as described.

JAMES ALSTON HARMON.
